(57) **CLAIM**

The ornamental design for a pump shroud, as shown and described.

DESCRIPTION

FIG. 1 is an isometric view of the pump shroud of the present invention mounted to a pump assembly;
FIG. 2 is a front plan view of the pump shroud;
FIG. 3 is a rear plan view of the pump shroud;
FIG. 4 is a left side view of the pump shroud;
FIG. 5 is a right side view of the pump shroud;
FIG. 6 is a top plan view of the pump shroud; and,
FIG. 7 is a bottom plan view of the pump shroud.

Those portions of the drawings shown in broken lines are included for illustrative purposes only and form no part of the claimed design.
